UNITED STATES PATENT OFFICE.

CHARLES REPETTI, OF NEW YORK, N. Y.

DESIGN FOR A CANDY-MOLD.

SPECIFICATION forming part of Design No. 34,617, dated June 4, 1901.

Application filed May 7, 1901. Serial No. 59,190. Term of patent 3½ years.

To all whom it may concern:

Be it known that I, CHARLES REPETTI, a citizen of the United States, and a resident of the city of New York, borough of Manhattan, in the county and State of New York, have invented and produced a new and original Design for a Candy-Mold, of which the following is a full, clear, and exact description.

Reference is to be had to the accompanying drawings, forming a part of this specification, in which—

Figure 1 is a bottom plan view of a candy-mold, showing my design; and Fig. 2 is a section on the line $x x$ of Fig. 1.

The leading feature of my design for a candy-mold consists in the dished body portion, within the bottom of which is formed the representation of a pan having in it the representation of a buffalo's head, and flags are arranged at opposite sides of the pan.

Referring particularly to the drawings, the

dish-shaped body portion is made circular, and pressed inward in the bottom of the body is the representation of a pan having a handle, and embossed in the pan is the representation of a buffalo's head, while at the opposite sides of the pan are American flags, which are also embossed and supported on sticks which appear to cross the body of the pan.

Having thus described my invention, I claim as new and desire to secure by Letters Patent—

The design for a candy-mold, as herein shown and described.

In testimony whereof I have signed my name to this specification in the presence of two subscribing witnesses.

CHARLES REPETTI.

Witnesses:

ISAAC MARX,
LOUIS P. SONDEHIM.
